FISH STRINGER

Daniel W. Helton, 115 Ruth St., Sikeston, Mo. 63801

Continuation-in-part of design application Ser. No. 406,243, Oct. 15, 1973. This application Dec. 9, 1974, Ser. No. 530,593

Term of patent 14 years

Int. Cl. D22—05

U.S. Cl. D22—22

Fig. 1

Fig. 2

Fig.3

FIG. 1 is a top plan view of a fish stringer showing my new design;

FIG. 2 is a side elevational view showing the side of said fish stringer; and

FIG. 3 is a bottom sectional view of said fish stringer taken along section line 3—3 of FIG. 2.

The side opposite the side shown in FIG. 2 is a mirror image thereof.

This is a continuation-in-part of my design application Ser. No. 406,243, filed Oct. 15, 1973.

I claim:

The ornamental design for a fish stringer, as shown and described.
